TYPOGRAPHICAL COMPOSING MACHINE

Paul Sckrabei, Berlin-Lubars, Germany, assignor
to Mergenthaler Linotype Company, Brooklyn,
N. Y., a company of New York

Application April 3, 1940, Serial No. 327,682
In Germany April 3, 1939

7 Claims. (Cl. 199—14)

This invention relates to typographical composing machines such as are known commercially under the registered trade mark "Linotype" and is more particularly concerned with 5 mechanism for adjusting the matrix line length in such machines.

Hitherto, when it has been desired to change the length of the line, it has been necessary to carry out an adjustment at four different places 10 on the machine, namely, on the assembler slide, the matrix line delivery carriage, the matrix line stop on the first elevator head and the movable vise jaw. In consequence of errors arising in one or more of these adjustments trouble has 15 frequently occurred, since, if too much or insufficient space is left in the matrix line, the matrices become jammed or tilted, thereby causing the machine to be stopped.

Again, a wrong adjustment may permit metal 20 to penetrate into the intervening spaces between the matrices or even prevent the matrices from being fully introduced into the line thereby again bringing the machine to a standstill.

It is one of the principal objects of the invention 25 to eliminate the above disadvantages and with this and other ends in view the same comprises a typographical composing machine of the kind referred to wherein common adjusting mechanism for the matrix line length is provided 30 for the assembler slide and the vise jaws and means operated from the machine are provided for returning the matrix line stop on the first elevator and the long finger to their original positions.

35 From another aspect the invention consists in a typographical composing machine of the said kind in which the assembler slide and vise jaws are connected by means of a member whereby common adjustment of their matrix length is 40 carried out and wherein the controlling mechanism for such length is independent of the said member.

To carry out the said adjustment, a guide rod 45 associated with the movable vise jaw may be extended the length of the said jaw and of the assembler slide and may be movable in the same direction as the said slide. The said rod may be provided with a fixed stop which is adapted to engage a counter-abutment of the assembler slide. 50 In order to compensate the movement of the vise, it is preferable to divide the guide rod by a coupling which is transversely releasable but quite rigid in the direction of adjustment, so that one 55 portion of the guide rod can partake in the movement when the vise frame is tilted downwardly, while the other portion remains in fixed guides on the machine.

In order that the invention may be more clearly 60 understood, one form which it may assume will

now be described with reference to the accompanying drawing in which:

Figure 1 is a view of a portion of a typographical composing machine showing the assembler slide and vise jaws and the upper portion of the 5 first elevator, the intermediate channel and the matrix delivery carriage;

Figure 2 is a section along the line A—B of Figure 1;

Figure 3 is a section along the line C—D of 10 Figure 1;

Figure 4 is a horizontal section showing the common adjusting mechanism for the vise jaw and the assembler slide;

Referring to the drawing:

15 1 is the assembler slide with the assembler finger 2. The assembler is designated with 3. On the assembler is located a small block 4 having a releasing pin 5, which, through the operation of a two-arm lever 6 actuates the releasing pawl 20 7, when the assembler ascends, whereby the long finger 8, on the left-hand side of the matrix delivery carriage is released so as to allow the same to strike against the line of matrices which is now raised further upwards between the long finger 25 8 and the short finger 9 of the matrix delivery carriage. As is already known, the release of the short finger takes place when the assembler reaches its uppermost position, so as to allow the matrix line to slide towards the left 30 30 through the intermediate channel 10, until it reaches the first elevator head 11. In the first elevator head 11 the matrix line comes up against the displaceable matrix line stop 12 and moves the latter along in front of it. The matrix line 35 stop is formed in known manner as a longitudinally displaceable bail, which is held in its temporary position of adjustment by a brake mechanism, not illustrated in the drawing. When the first elevator ascends into the distributing position, the matrix line stop 12 is engaged by the longitudinally movable pusher 13 and is returned thereby into its initial position by the operation of the link 14 and the lever 15 which is secured to a rock shaft 15a controlled from the cam shaft 45 of the machine. The matrix delivery carriage is returned by means of the link 16 which is attached thereto and to the lever 17. The said lever is fixed to a rock shaft 18. The movement of the carriage to the left is brought about by 50 means of the spring 19 bearing on the lever 20 which is secured to the rock shaft 18. The return movement through the link 16 and lever 17 is controlled by means of a cam (not shown) engaging roller 22 on the arm 23 secured to the shaft 18. Upon the return of the carriage, the long left-hand finger 8 will be restored to the 55 original position from which it had previously been released.

5 The left-hand vise jaw 24 of the vise frame is adjustable to the line lengths required in the manner usual in machines of the kind under consideration. A longitudinally displaceable rack bar 25 provided with a spring controlled pawl 26 on the left hand side of the machine is used for adjusting the jaw 24, and the said pawl is releasable by means of a lever 27. A fine adjustment of the jaw 24 relatively to the rod 25 may be carried out by means of a set screw 28.

10 A guide rod 29 which is adapted to extend within the reach of the assembler slide is fastened to the adjusting mechanism for the jaw 24, and is guided in guideways 30, 31, in the same direction of movement as the assembler slide. The said guide rod 29 is subdivided into two and the parts are joined together by a cross pin 32 which at one end is secured to the left-hand part of the rod 29 and at the other end engages an aperture 15 in the right-hand part thereof. The result of this is to ensure a coupling which is releasable in the transverse direction, but rigid in the direction of adjustment which makes it possible for the left-hand portion of the guide rod to partake 20 in the movement when the vise-frame is tilted downwardly, whereas the right-hand portions remains in its guideways. To facilitate its engagement, the coupling pin 32 is pointed at its free end.

25 30 Upon the rod 29 is mounted a stationary stop 33 against which a counterabutment 34 of the assembler slide is adapted to engage. The counterabutment 34 is provided with a finely adjustable screw 35 and is located on a lever 36 rigidly connected to the assembler slide 1, and which extends forwards within the reach of the guide rod 29. A downwardly rockable detent 37 is located on the stop 33, which detent, after being rocked downwardly, causes the counterabutment 34 to perform a small supplemental movement thereby 35 allowing, as usual, the introduction of a last matrix. One end of the rod 29 is provided with scale divisions, which are employed for adjustment of the desired line length.

40 45 When it is desired to make a change in the line measure, it is only necessary to actuate the adjustable mechanism located on the left hand side of the machine, that is to say, the releasing lever 27, whereupon the common adjustment of the assembler slide and of the vise jaw may be effected by displacement of the rack bar 25, and the guide rod 29 connected thereto. At the same time the remaining positions on the machine, that is to say, the matrix line stop 12 and the long finger 8, will be automatically adjusted to the selected line-length.

50 60 The invention is not restricted to the constructional form illustrated, inasmuch as alterations in detail may be carried out without going beyond the scope of the invention, for instance, other preferred known means of adjustment may be selected; the adjusting mechanism may also be mounted on a different part of the machine. Further, the vise jaw and the assembler slide may 65 also be connected by separate means to a common adjusting mechanism, in which case these separate means may each contain a special fine adjusting mechanism.

65 70 Having described my invention, I declare that what I claim and desire to secure by Letters Patent is:

1. In a typographical composing machine of the kind referred to the combination of an assembler slide and vise jaws with common adjusting means for the length of the matrix line on said slide and jaws and means independent of said adjusting means and operated from the machine for returning the matrix line stop on the first elevator and the long finger on the delivery carriage to their original positions after movement of the line therefrom. 10

2. In a typographical composing machine of the kind referred to the combination of an assembler slide and vise jaws with a rod connecting said slide and jaws operable to adjust the length of the matrix line on said slide and jaws and adjusting mechanism for such length independent of said rod. 15

3. In a typographical composing machine of the kind referred to the combination of an assembler slide and vise jaws with common adjusting means for the matrix length on said slide and jaws, said slide and jaws being separately connected to said adjusting means. 20

4. In a typographical composing machine of the kind referred to the combination of an assembler slide and vise jaws with a rod connecting said vise jaws and said slide, said rod having a stop thereon engaging an abutment on said slide, a pawl and rack bar engaging said vise jaws and said rod and operable to adjust the length of the matrix line on said slide and jaws, a detent on said stop adapted to be rocked so as to cause said abutment to perform a supplemental movement to permit the introduction of an additional matrix. 35

5. In a typographical composing machine of the kind referred to the combination of an assembler slide and vise jaws with common adjusting mechanism for the length of the matrix line on said slide and jaws, and a pusher member engaging the matrix line stop to return the same to its original position upon the matrix line ascending to the distributing position in the first elevator. 40

6. In a typographical composing machine of the kind referred to the combination of an assembler slide and vise jaws with common adjusting mechanism for the length of the matrix line on said slide and jaws, a pusher member engaging the matrix line stop in its uppermost position in the first elevator to return the same to its original position and lever mechanism controlled by the cam shaft of the machine to return the delivery carriage to the assembler. 45

7. In a typographical composing machine of the kind referred to the combination of an assembler slide and vise jaws with a rod connecting said vise jaws and said slide, said rod having a stop thereon engaging an abutment on said slide, a pawl and rack bar engaging said vise jaws and said rod and operable to adjust the length of the matrix line on said slide and jaws, a detent on said stop adapted to be rocked so as to cause said abutment to perform a supplemental movement to permit the introduction of an additional matrix, a pusher member engaging the matrix line stop in its uppermost position in the first elevator to return the same to its original position and lever mechanism controlled by the cam shaft of the machine to return the delivery carriage to the assembler. 50
